(57) **CLAIM**

The ornamental design for a light kit as shown and described.

DESCRIPTION

FIG. 1 is a bottom perspective view of a light kit showing my new design in a ceiling fan environment.

FIG. 2 is a top perspective view of the light kit.

FIG. 3 is a bottom perspective view of the light kit.

FIG. 4 is a top view of the light kit.

FIG. 5 is a bottom view of the light kit; and,

FIG. 6 is a front view of the light kit.

The broken lines illustrate portions of the light kit and form no part of the claimed design.

1 Claim, 6 Drawing Sheets

FIG. 2

FIG. 4

FIG. 5

FIG. 6
